UNITED STATES PATENT OFFICE.

EMERY D. WATERBURY, OF SAWTELLE, CALIFORNIA.

MILK-CAN OPENER AND SEAL.

No. 868,512.

Specification of Letters Patent.

Patented Oct. 15, 1907.

Application filed August 9, 1906. Serial No. 329,916.

To all whom it may concern:

Be it known that I, EMERY D. WATERBURY, a citizen of the United States, residing at Sawtelle, in the county of Los Angeles and State of California, have 5 invented a new and useful Device for Milk-Can Openers and Seals, of which the following is a specification.

The object of this invention is to provide a device capable of being readily attached to cans for making 10 openings or incisions in the tops thereof, and also sealing such openings when desired.

The invention will be hereinafter fully set forth and particularly pointed out in the claims.

In the accompanying drawings, Figure 1 shows the 15 device applied to a condensed-milk can. Fig. 2 is a similar view showing the openings uncovered. Fig. 3 is a view in perspective of the device, detached.

Referring to the drawings, A designates a clamp composed of a bar of thin spring metal, each end of 20 which is bent downwardly at right angles and notched, at K, and one of the bent portions is provided with a lateral lip O. Pivotally secured to the bar A, at the center thereof, as at E, is a second bar B, also of spring metal, to the outer ends of which are secured knobs 25 C and spurs D, the latter extending beneath bar B. The spurs D constitute the punching media.

In practice, the clamping bar A is secured to a can by first placing one of the downwardly bent portions in engagement with the edge of the can top, the 30 notch K taking under the edge of such top, and by

pressure on lip O the other bent portion is then forced down into engagement with the can top. After bar B has been moved to the desired position, a blow or pressure on knobs C will force the spurs D through the can-top. To then discharge all or a portion of the 35 contents it is only necessary to withdraw the spurs and turn bar B on its pivot. To seal the can, bar B is again turned to bring the spurs into the openings, into which they will be forced by the pressure of their carrying member. Each spur carries a gasket x 40 to hermetically seal the respective openings. When the can is emptied, the device may be removed and applied to another can.

I claim as my invention:

1. As an article of manufacture, the herein described 45 can-punching device comprising a bar of spring metal hooked at its opposite ends, a second bar pivotally secured to the first mentioned bar, spurs carried by said second bar at the ends thereof, and gaskets between said spurs and said second member.

2. As an article of manufacture, the herein described 50 can-punching device comprising a member of thin metal having its ends bent downwardly and formed with notches to engage a can-top at the opposite points thereof, one of said downwardly bent portions having a lateral flange, a 55 second member also of spring metal pivotally secured to the first mentioned member, knobs mounted on the ends of said second member, and spurs beneath said knobs for forming openings in the can-top.

EMERY D. WATERBURY.
